UNITED STATES PATENT OFFICE.

BRUCE CLARK WHITE, OF PITTSBURG, PENNSYLVANIA.

PUMP.

SPECIFICATION forming part of Letters Patent No. 743,361, dated November 3, 1903.

Application filed June 29, 1901. Serial No. 66,465. (No model.)

To all whom it may concern:

Be it known that I, BRUCE CLARK WHITE, of Pittsburg, in the county of Allegheny and State of Pennsylvania, have invented certain new and useful Improvements in Pumps; and I do hereby declare that the following is a full, clear, and exact description thereof, reference being had to the accompanying drawings, and to the letters of reference marked thereon, which form a part of this specification.

A pump constructed in accordance with my invention has a rotary pump chamber or cylinder and a reciprocating piston and is more especially intended for use in pumping semi-fluid materials, such as slaked lime; but a pump embodying the same principles of construction is adapted to be used for pumping all kinds of liquids and gases.

The invention consists in the matters hereinafter described, and pointed out in the appended claims.

In the accompanying drawings, Figure 1 is a sectional view of the pump, taken, on a plane perpendicular to the axis of rotation of the rotative part thereof, on line 1 1 of Fig. 3. Fig. 2 is a cross-section thereof, taken on line 2 2 of Fig. 3. Fig. 3 is a cross-section taken on line 3 3 of Fig. 1. Fig. 4 is an exterior view of the pump-casing, the supporting shaft for the eccentric being shown in section. Fig. 5 is a side view of the pump, showing one head of the casing removed and the interior working parts in elevation. Fig. 6 is a perspective view showing the connected pistons of the pump and the actuating-eccentric for said pistons. Fig. 7 is a view in perspective of the rotative head which contains the pump-chambers. Fig. 8 is a view in section of a form of pump embodying the main features of my invention, differing somewhat from the form shown in the preceding figures. Fig. 9 is a sectional view taken on line 9 9 of Fig. 8.

As shown in the said drawings, the exterior casing or inclosure of the pump is of cylindric form, and consists of a cylindric wall A and end walls or bonnets A' and A''. Said casing is provided with an inlet B and an outlet B', which intersect or open through the cylindric wall of the casing and are herein shown as formed by means of integral tubu-

lar necks or extensios a a' on the cylindric wall A.

C indicates a rotative head which is located within the casing and is provided with a cylindric exterior surface fitting the interior surface of the casing. Said head is provided with a rigidly-affixed shaft C², which passes through the bonnet A' of the casing, being mounted in a suitable bearing on said bonnet and is herein shown as provided with a drive-pulley C³, by which it may be rotated.

D D indicate two pump-pistons, which are rigidly connected by an intermediate connecting portion, herein shown as consisting of metal webs d d, cast integral with the pistons D D. Said pistons are mounted to slide in radial pump-chambers C' C' in the head C, which pump-chambers at their outer ends intersect or open through the exterior cylindric surface of the said head, at opposite sides thereof. Said pump-chambers are formed by the end portions of a transverse recess formed in the head C, said recess being shaped at its outer parts, adjacent to the periphery of the head, to form the walls of the pump-chambers and having a central enlarged part to accommodate the piston-actuating devices. As herein shown, the transverse piston-receiving recess in the head is open through the side face of said head adjacent to the bonnet A' of the casing, the said recess in this instance having the form of a transverse groove in the end of the head. The pistons are made of square form, as seen in end view, and the pump-chambers or end portions of the transverse recess of the head are of corresponding shape and are provided with lateral surfaces c c for contact with the sides of the pistons D D and with a flat end bearing-surface c' for contact with adjacent end surfaces of the said pistons, while the opposite end surfaces of said pistons are adapted to bear against the flat inner face of said bonnet A', as clearly shown in Fig. 2. From this arrangement it is obvious that the inner surface of the bonnet A' constitutes, in effect, one wall of each pump-chamber, the other walls of which are formed by the bearing-surfaces c c and c'.

The making of the pump-chambers and pistons of rectangular form or with flat sides and

the forming of said chambers by a transverse recess which opens through one of the flat sides of the head is a feature employed to enable the parts to be easily made and readily taken apart and assembled, as hereinafter more fully pointed out, and is not essential so far as the operation of the other features of the pump is concerned.

- E indicates an eccentric which is mounted 10 on the side wall or bonnet A² and which during the rotation of the head C is adapted by its engagement with the connected pistons to give reciprocatory movement to the pistons transversely in the head. As a means for affording engagement of said eccentric with the connected pistons, said pistons are shown as provided in the part connecting the same with a transversely-arranged slot or opening having opposite parallel bearing-surfaces d' d', between which the eccentric is inserted and against which it bears at its opposite sides as the head and pistons revolve in such manner as to give reciprocatory movement of the connected pistons in the head. In the 25 particular construction shown, wherein the pistons D D are joined by two connecting-webs d d, the parallel bearing-surfaces d' d' for the said eccentric E are shown as formed on two parallel cross-walls d² d², which are 30 cast integral with the said webs d d.
- In the operation of the main parts described the head C is continuously driven or rotated by suitably-applied driving means, and as the said head turns or revolves within the 35 casing the connected pistons D are through their engagement with the eccentric E moved or shifted endwise in the head, so as to bring the outer end of each piston alternately flush, or nearly so, with the outer surface 40 face of the head, or, in other words, so as to give each of the pistons a reciprocatory movement inward and outward in the pump-chamber in which it moves, said eccentric being so located or disposed with respect to the inlet 45 and outlet openings of the pump that each piston will make its inward or suction stroke when its pump-chamber is opposite or in communication with the inlet-opening and will make its outward or ejecting stroke when the 50 said pump-chamber is opposite or in communication with the outlet-opening. As the result of this mode of operation, the material to be pumped, which is delivered to the pump-casing through the inlet B, will be drawn or 55 sucked into each pump-chamber by the retraction of the piston in said pump-chamber. When it is opposite or in communication with said inlet-opening, the material will be held in the pump-chamber during the passage 60 thereof from the inlet to the outlet opening and will be forced or ejected from the pump-chamber and outwardly through said outlet-opening when the pump chamber is opposite or in communication with said outlet-opening.
- 65 The eccentric E is stationary or immovable while the pump is in operation and may be

fixedly attached to the bonnet A²; but in order to afford adjustment of the position of the said eccentric for changing the movement of the connected pistons, so as to modify or reverse the action of the pump, the said eccentric E is shown as connected by a crank-arm e with a supporting-shaft E', which is mounted and adapted to turn in the bonnet A² and is provided outside of said bonnet 75 with means whereby the eccentric may be swung or moved and rigidly locked in its changed positions. A simple form of device for this purpose is shown in the drawings, consisting of a hand-lever F, attached to the shaft E' outside of the bonnet A² and provided with a stud f, adapted for contact with two stop projections a² a² on the bonnet A², so as to limit the movement of the hand-lever at opposite limits of the movement of the eccentric, a set-screw f' being shown as inserted through the bearing of the shaft E' and adapted to engage the said shaft, so as to rigidly hold the same in position when the eccentric is at either limit of its bodily movement or at a desired intermediate point in such movement. Said eccentric E is shown in full lines in the several figures of the drawings as arranged in position to so operate the pump-pistons that material will be drawn into the pump-chambers from the inlet B and ejected therefrom through the outlet B'; but if the said eccentric be shifted to the position shown in dotted lines in said Fig. 1 a reverse movement will occur.

If the eccentric E were made of cylindric form, it is manifest that the pump-pistons would be continuously in movement during the rotation of the head, and while a pump having such cylindric eccentric would be operative, yet in order to produce the best results, especially in a pump designed for operating with a liquid or semiliquid substances, it is desirable that the pistons should be in movement only while the pump-chambers are in communication with the inlet and outlet openings and that the said pistons should have no movement during the time of the passage of the said pump-chambers from the inlet to the outlet openings and when said chambers are entirely closed at their outer ends by the annular bearing-surface of the casing. To afford movement in the pump-pistons in the manner described, I make the eccentric E of cam shape at its bearing-surface or periphery which engages the side-walls of its bearing-slot, and I give the cam-surfaces of the eccentric such shape that the inward stroke of each piston will take place during the time the pump-chamber is in communication with the inlet-opening and that it will remain stationary in its pump-chamber during the time said chamber is moving along and is closed by the portion of the annular bearing-surface of the casing between the inlet and outlet openings and will move outwardly when the said chamber is in communication with the outlet-

opening, beginning said outward movement after the said pump-chamber has reached and is in communication with the said outlet-opening, as shown in Fig. 1, and completing the said outward movement at the time said pump-chamber is fully in register with said outlet-opening, so that all of the material will be discharged from the pump-chamber before the latter begins to move past or away from the said outlet-opening. As a result of this movement in the case of a sluggish-flowing material, the quantity of the same within the pump-chamber will be drawn bodily into the pump-chamber and ejected bodily outward therefrom without in either case being forced through any narrow space or channel, and the pump will operate even should solid objects, such as pebbles or stones, be contained in the material being handled. This movement of the piston is provided, in the pump shown in the drawings, by making the cam-surface of the cam-shaped eccentric E with three prominences or projections $e^1 e^2 e^3$, connected by three arc-shaped or cylindric intermediate surfaces $e^4 e^5 e^6$, the prominences being diametrically opposite the intermediate surfaces and the cam being so proportioned that its opposite sides will always be in contact with both of the parallel bearing-surfaces $d^2 d^2$. The inlet and outlet ports being arranged diametrically opposite each other, one of the prominences is directed toward one of the ports, (the outlet-port B' in Fig. 1,) and the intermediate portion of the arc-shaped surface e^1 at the opposite side of the eccentric is directed toward the opposite port, (the inlet-port B, Fig. 1,) so that each piston will reach the limits of its throw in both directions when it is opposed to the said ports. Manifestly the pistons will have practically no movement when the sides of the transverse slots of the pistons are engaged by the prominences $e^2 e^3$ and arc-shaped surfaces $e^5 e^6$.

As hereinbefore described, the piston-actuating eccentric E is arranged to be shifted in position so as to produce a reverse movement in the pistons, so that each piston will be drawn inwardly when the pump-chamber is in communication with the outlet-opening B' and forced outwardly when the pump-chamber is in communication with the inlet-opening B, thereby reversing the direction of action of the pump. As an illustration of the utility of this arrangement, if the pump illustrated be used for pumping slaked-lime paste from a tank containing the same, in this case the inlet B will be connected with the bottom portion of the tank containing the lime, and so long as the pump is operating normally or in the usual way the lime will be withdrawn from the tank and forced out through the outlet of the pump-casing. It is found, however, that if the lime be allowed to settle in the tank it becomes solidified, so as to no longer readily flow to the pump; but if during the periods it is not de-

sired to deliver lime from the tank the action of the pump be reversed, as described, the pump will then operate as an air-pump to force the air backwardly from the inlet to the outlet and into the body of lime, thus keeping the same stirred up or agitated and in a condition to readily flow and to be easily pumped when the delivery of the lime from the tank is resumed.

I have shown in the accompanying drawings a valved water-pipe G communicating with the pump-casing between the inlet B and the outlet B', said pipe serving to supply water under pressure to the pump-chambers at this point. Water thus supplied when the action of the pump is reversed will be forced by the pressure in the said pipe into the pump-chambers when the pistons are retracted and will when the pistons move outwardly in approaching the inlet-port be forced or pumped into the mass of lime in the tank or in the passage from the tank to the pump, with the result of making the lime more fluid and facilitating its flow toward and its subsequent movement through the pump.

The construction in the revolving head illustrated, wherein the transverse recess which forms the pump-chamber is made in the form of a rectangular slot in the end or flat face of the head, so that the bonnet or end wall of the casing forms one wall of each pump-chamber and the pistons slide in contact with said bonnet, has the advantage of greatly facilitating the construction of the head because enabling the bearing-surfaces of the pump-chambers to be finished by the use of a planer or similar tool and also because it permits the pistons to be removed for repairs by merely taking off the bonnet A² without disturbing the head and its shaft. Manifestly when the said bonnet is removed the eccentric will be removed with it and the interior parts will be exposed, as seen in Fig. 5, so that not only may the pistons be taken out, but by turning the head into proper position access may be had to the inlet and outlet ports for inspecting or cleaning the same.

The making of the eccentric E adjustable in position, as described, has the important advantage not only of enabling the action of the pump to be reversed, but also of enabling its capacity to be varied, the shifting of said eccentric a distance less than that required for reversing the pump having the effect of shortening the stroke of the pistons and lessening the area of the pump-chambers when the pistons are retracted. The adjusting devices for the eccentric may therefore be employed to merely shorten the piston-stroke without reversing the pump action.

An important advantage gained by the employment of the general features of the construction described—namely, the casing having an annular bearing-surface and parts opening therethrough and the piston-carrying head having pump-chambers which open through

the bearing-surface of said head—is that of avoiding the loss of capacity and therefore of power which arises, in a pump having inlet and outlet valves, through the escape of the fluid through the valves in the opening and closing of the same, technically known as "slip." Manifestly in the pump herein shown slip is entirely avoided because of the fact that no valves are employed, and the open ends of the pump-chambers are closed by the bearing-surface of the casing, along which the said chambers move in passing from the inlet to the outlet port, so that all of the material drawn into the pump-chamber is retained therein, and all of such material is ejected from the pump at each outward stroke of the pistons.

So far as is concerned the lateral removal of the pump-pistons when the bonnet A^2 is removed, the pump-chambers and said pistons need not be made of rectangular form, it being only necessary for this purpose that the said chambers and pistons should be so shaped as to admit of the lateral removal of the pistons from the chambers and that the pistons should have flat faces for contact with the inner face of the bonnet A^2 , on which said pistons slide both circumferentially and radially. The square form in the pump chambers and pistons is, however, in connection with a square form in the inlet and outlet ports, preferred because affording a maximum area of opening between the said ports and the pump-chambers, with a minimum degree of angular movement in the rotative head, it being obvious that if the pump chambers and pistons were round, for instance, the chamber would need to overlap the ports for a considerable distance before the opening between them would be of any considerable size, and the chambers and ports, if made circular, extend through a longer arc in the circumference of the head than if made of rectangular form, the areas of the openings in the two cases being the same.

In Figs. 8 and 9 I have shown a simple form of pump embodying the main features of my invention and illustrative of the same in its broadest aspect, this form of pump being more especially adapted for pumping liquids. In this instance, H indicates the casing, which is of cylindric form and provided with an integral side wall H' and a removable side wall H^2 . I indicates the rotative head, which is provided with a peripheral cylindric bearing-surface in contact with the corresponding inner cylindric surface of the casing. In said head I is formed a transverse cylindric opening which forms two pump-chambers and in which are located two pistons J , connected by a bar J' . The bar J' is provided with a transverse slot j , which is engaged by an eccentric-pin K , affixed to the removable side wall H^2 . L and L' are inlet and outlet passages in the casing, said passages communicating with ports l , which extend along the inner bearing-face of the

casing, circumferentially thereof, and each of which extends nearly half-way around the casing, the two ports being separated from each other at each side of the casing by spaces slightly longer than the diameter of the pump-chambers.

The operation of the pump shown in Figs. 8 and 9 is generally the same as that shown in the other figures of the drawings. In this instance, however, the pump-pistons are continuously in movement during the rotation of the head, and liquid from the inlet-port flows into one pump-chamber continuously while one pump-piston is making its instroke, while liquid is ejected through the outlet-port continuously while the opposite piston is making its outstroke, the ports l and l' being extended around the casing far enough to afford the inflow and outflow of the liquid during substantially the entire stroke of the connected pistons.

I claim as my invention—

1. A pump comprising an outer casing provided with an interior cylindric bearing-surface and having inlet and outlet ports opening through said bearing-surface, a rotative head mounted in said casing having an exterior annular bearing-surface in contact with the bearing-surface of the casing, said head being provided with a pump-chamber which intersects and opens through its exterior annular bearing-face, a piston sliding in said pump-chamber, and an eccentric which engages said piston and gives reciprocatory movement thereto in the rotation of said head, said eccentric being so shaped as to hold the piston at the inward and outward limit of its stroke while the outer end of the cylinder is moving along the bearing-surface of the casing between and is cut off from said ports, and to move the piston inwardly and outwardly during the time the cylinder is in communication with said ports.

2. A pump comprising a casing having an outer cylindric wall and end walls, and provided with an interior, cylindric bearing-surface and with inlet and outlet ports, opening therethrough, a rotative head in said casing provided with an exterior cylindric bearing-surface and which closely fits within the casing with its exterior cylindric bearing-surface in contact with the interior cylindric surface of the casing, said head being also provided with a transverse recess the end portions of which form pump-chambers which open at their outer ends through the outer cylindric bearing-surface and also open laterally through the end surface of the head, connected pistons which fit and slide in said pump-chambers, an eccentric which engages and gives motion to the connected piston, one of the end walls of the casing being adapted to support said eccentric and having a flat inner face in contact with the end surface of the head and with the adjacent side faces of the pistons.

3. A pump comprising a casing having an

annular bearing-surface and provided with inlet and outlet ports in said bearing-surface, a rotative head provided with an annular bearing-surface and with a radial pump-chamber opening through said bearing-surface, a piston in said pump-chamber, an eccentric for actuating said piston, a shaft mounted on the casing and provided with a crank-arm to which said eccentric is attached, an actuating-lever attached to the said shaft outside of the casing and coacting means on the casing and lever for determining the position of the eccentric.

4. A pump comprising a casing having an interior, annular bearing-surface, and provided with inlet and exit ports which open through said bearing-surface, a rotative head provided with an external annular bearing-surface and with a pump-chamber which opens through said bearing-surface, a piston

in said pump-chamber, an eccentric for giving motion to the piston, said eccentric being adjustable in position to reverse the action of the pump, and a valved water-supply pipe which communicates with the pump-chamber at a point between the said inlet and outlet ports and at such distance from the inlet-port that it will, when the motion of the pump is reversed, discharge into the pump-chamber when the piston is retracted in the approach of the pump-chamber toward said inlet-port.

In testimony that I claim the foregoing as my invention I affix my signature, in presence of two witnesses, this 16th day of May, A. D. 35 1901.

BRUCE CLARK WHITE.
